(57) **CLAIM**

The ornamental design for a bracket stand, as shown and described.

DESCRIPTION

FIG. 1 is a top front perspective view of a bracket stand in accordance with an embodiment of the claimed design; FIG. 2 is a right side elevation view of the design of FIG. 1; FIG. 3 is a left side elevation view of the design of FIG. 1; FIG. 4 is a front elevation view of the design of FIG. 1; FIG. 5 is a rear elevation view of the design of FIG. 1; FIG. 6 is a top plan view of the design of FIG. 1; FIG. 7 is a bottom plan view of the design of FIG. 1; FIG. 8 is a top front perspective view of a bracket stand in accordance with another embodiment of the claimed design; FIG. 9 is a right side elevation view of the design of FIG. 8; FIG. 10 is a left side elevation view of the design of FIG. 8; FIG. 11 is a front elevation view of the design of FIG. 8; FIG. 12 is a rear elevation view of the design of FIG. 8; FIG. 13 is a top plan view of the design of FIG. 8; and, FIG. 14 is a bottom plan view of the design of FIG. 8.

The dash-dash broken lines in the figures represent unclaimed subject matter and form no part of the claimed design.

The dot-dash broken lines in the figures represent a boundary between claimed and unclaimed subject matter and form no part of the claimed design.

The labels used herein to describe orientation (e.g., front, rear, left, right) are merely for reference and are not intended to limit the interpretation of the design.

1 Claim, 14 Drawing Sheets
